UNITED STATES PATENT OFFICE.

ADOLPH C. RECKER, OF OAKVILLE, CONNECTICUT, ASSIGNOR TO WATERBURY MFG. CO.,
OF WATERBURY, CONNECTICUT, A CORPORATION.

VACUUM-BOTTLE.

1,260,047.

Specification of Letters Patent. Patented Mar. 19, 1918.

Application filed February 26, 1917. Serial No. 150,913.

To all whom it may concern:

Be it known that I, ADOLPH C. RECKER, a citizen of the United States, residing at Oakville, in the county of Litchfield and State 5 of Connecticut, have invented a new and useful Improvement in Vacuum-Bottles; and I do hereby declare the following, when taken in connection with the accompanying drawings and the characters of reference 10 marked thereon, to be a full, clear, and exact description of the same, and which said drawings constitute part of this application, and represent, in—

Figure 1 a view of my improved vacuum 15 bottle in elevation, a portion of it being shown in vertical section, and its case being shown in section.

Fig. 2 a broken detail sectional view on an enlarged scale of the metal shell, showing 20 one of the finger-grips.

My invention relates to an improved vacuum bottle, the object being to produce the shells of such bottles with finger-grips, whereby the bottles may be more conveniently and safely handled without slipping in the hand.

With these ends in view, my invention consists in a vacuum bottle having its shell provided with finger-grips, as will be hereinafter described and pointed out in the 30 claims.

In carrying out my invention as herein shown, the sheet-metal shell 2 of the bottle is struck up to provide it with two circumferential bands of pocket-like finger-grips, each consisting of an inwardly struck circular flat portion 3 and an outwardly struck bead 4 surrounding the same. Since the deeper the finger-grips, the better the hold 40 upon the bottle, the best results will be secured by striking the metal inwardly on the one hand, as much as permitted by the corrugated paper-wrapper 6 which surrounds the outer wall 7 of the bottle proper or 45 glass container the inner wall 8 of which is separated from the wall 7 thereof by a vacuum chamber 9. On the other hand, the metal of the shell 2 will be struck outwardly as much as practicable without interfering 50 with the insertion of the bottle into the cylindrical case 10 which is furnished with a cap 11. The external diameter of the paper-wrapper 6 and the internal diameter of the case 10 constitute the predetermined limit 55 its within which the metal shell may be

struck inwardly and outwardly in the production of the finger-grips. As shown, the two bands of finger-grips are flanked on either side by circumferential beads 12 which give an ornamental and distinctive character 60 to the shell and also assist the hand to some extent in gripping the same. The shell is also formed with a circumferential rib 13 located at its lower end and at its upper end with a corresponding rib 14, and furnished 65 with a screw cap 15 having a rib 16 and receiving a screw cup 17, all of familiar and well known construction.

By providing the shell with two circumferential bands of finger-grips, my improved 70 vacuum bottle may be handled with superior convenience and safety. If desired, a single band of finger-grips might be employed in place of two bands of finger-grips, or the finger-grips might be arranged in other symmetrical or non-symmetrical ways, the essential feature of my invention being the provision of the sheet-metal shell of a vacuum bottle with a plurality of pocket-like finger-grips however produced and arranged. 75 Nor do I limit myself to striking the metal 80 of the shell so as to form circular grips, as the particular form of the grips may be varied so long as their pocket-like character is retained.

I claim:—

1. The combination with a cylindrical glass vacuum-bottle, of a cylindrical sheet-metal shell therefor provided with a plurality of circumferentially arranged segregated finger-grips adapted in size to receive the tips of the fingers of the user of the bottle and produced by striking the metal of the shell inwardly to form the bottoms of the grips, and outwardly to form beads around 90 said grip-bottoms, whereby finger-grips of the maximum efficiency are secured within the limits prescribed by the glass bottle and the case into which the shell is introduced for the protection of the device as a whole. 95

2. The combination with a cylindrical glass vacuum-bottle, of a shock-absorbing envelop therefor, and a cylindrical sheet-metal shell having a plurality of circumferentially arranged segregated finger-grips 105 adapted in size to receive the tips of the fingers of the user of the bottle and produced by striking the metal of the shell inwardly to form the bottoms of the grips, and outwardly to form beads around said grip- 110

bottoms, whereby finger-grips of the maximum efficiency are secured within the limits prescribed by the said shock-absorbing envelop and the cylindrical case into which the 5 shell is introduced for the protection of the device as a whole.

In testimony whereof, I have signed this

specification in the presence of two subscribing witnesses.

ADOLPH C. RECKER.
